UNITED STATES PATENT OFFICE.

WELLINGTON W. MUIR, OF LOCKPORT, NEW YORK.

PROCESS OF AND APPARATUS FOR COOLING INTERNAL-COMBUSTION ENGINES.

Application filed February 15, 1922. Serial No. 536,827.

To all whom it may concern:

Be it known that I, WELLINGTON W. MUIR, a citizen of the United States, residing at Lockport, in the county of Niagara and 5 State of New York, have invented certain new and useful Improvements in Processes of and Apparatus for Cooling Internal-Combustion Engines; and I do hereby declare the following to be a full, clear, and 10 exact description of the invention, such as will enable others skilled in the art to which it appertains to make and use the same.

This invention relates to a cooling system for internal combustion engines, wherein a 15 double impeller pump is employed, and has for its object to provide a method and an apparatus which will be simple in construction, certain in action, and more efficient in use than those heretofore proposed.

20 With these and other objects in view, the invention consists in the novel steps and combinations of steps constituting the process and in the novel parts and combinations of parts constituting the apparatus, all as 25 will more fully appear hereinafter and be particularly pointed out in the claims.

Referring to the accompanying drawings forming a part of this specification, in which like numerals designate like parts in all the 30 views:

Figure 1 is a diagrammatic, partially sectional view of a cooling system made in accordance with this invention; and

35 Figure 2 is a similar view of a somewhat modified form of the invention.

1 indicates any suitable engine jacket, 2 the normal level of the cooling fluid in said jacket, 3 a steam or vapor space above the level 2, 4 a pipe conveying the generated 40 steam or vapor into the top 5 of a condenser 6, and 7 a space or tank at the bottom of said condenser. 8 indicates a connection from said tank 7 to the top side of a double impeller pump 9; 10 a pipe leading from the 45 double impeller pump 9 back into the jacket 1, and 11 indicates branches of said pipe 10 to facilitate the circulation of the cooling fluid through the jacket 1. From the top 50 of the jacket 1 beginning at the water level 2, is a connection 12 joined to a pipe 13 which communicates with the under side 14 of the impeller pump 9, as shown.

The operation of this invention will be

clear from the foregoing, but may be briefly summarized as follows:

The level of the water in the jacket being brought to the point 2, steam or vapor will be generated and pass through the pipe 4 down into the condenser 6, where it will be brought to the liquid state and collected in the tank 7. From the tank 7 it will be pulled by the double impeller pump 9 through the pipe 8 and forced through the pipe 10 back into the jacket. As the liquid is thus returned to the jacket and the level 55 thereof brought to the connection 12 the said liquid will overflow into said pipe 13 and be brought to the under side 14 of the impeller pump 9, so that said under side of said pump will circulate the liquid around and 60 around through the pipes 10 and 13 into and out of the jacket and said pump will maintain this circulation so long as there is 65 enough liquid in the jacket to overflow into the pipe 13. Further, so long as the flow 70 of liquid from the tank 7 and from the pipe 13 are about equal, the pressure on the top 15 of said pump and on the bottom 14 thereof will be about the same, and therefore the 75 cooling action will be about the same in the 80 jacket and in the condenser 6.

On the other hand, should the pressure in the pipe 13 rise higher than that in the pipe 8, the pressure at the point 16 in the pump 9 will overbalance the pressure from the 85 pipe 8 in the upper compartment 15 of said pump, and thus will the liquid cease to be drawn from the tank 7 and only be circulated through the pipes 10 and 13. This 90 ceasing of the flow of liquid from the tank 7 will cause steam to accumulate in the condenser 6 and condensed steam to accumulate in the tank 7, until the pressure in the pipe 8 again equals that in the pipe 13.

On the other hand, should the level in the 95 jacket 1 decrease so that the liquid leaves the pipe 13, then the pump 9 can only pull liquid from the tank 7, with the result that the level in the jacket 1 will rise sufficiently 100 as to again cause liquid to overflow into the pipe 13. In other words, it will now be clear that this system enables one to employ a single pump 9 and to maintain an equal circulation, or a balanced circulation, through the jacket and through the condenser. This 105 is a feature of distinct advantage in sys-

tems for cooling internal combustion engines, because it insures at all times an efficient circulation around the cylinder walls, thus avoiding steam pockets and the over heating of the local spots.

In the somewhat modified form of the invention illustrated in Figure 2, the operation and construction is substantially the same as that disclosed in Figure 1, but with the following changes: The lower portion of the condenser 6 is provided with a partition or diaphragm 20 terminating in the tube or pipe 21 extending well below the liquid 22 in the tank 7, and a passage 23 inside the condenser is located outside said diaphragm 20 in order that it may serve as a vent for the system. The pipe 10 leading from the pump 9 into the jacket 1 instead of being provided with the branches 11 shown in Figure 1 is provided with the goose neck 25 and said goose neck is provided with a perforation 26 located somewhat above the normal level 2 of the liquid, which perforation not only prevents the goose neck from filling with liquid and thus acting as a siphon to empty the jacket back into the pump, but it also serves to receive steam from the space 3, which steam exerts an equal pressure on the fluid in both branches of the goose neck and thus aids to maintain the level of the liquid at the point 2.

In the form illustrated in Figure 1, the double check valves 45 and 46 prevent the liquid from returning to the pump 9. The provision of the diaphragm 20 and pipe 21 in the tank 7 enables the operator to collect and condense any alcoholic or other vapors which may have escaped condensation in the condenser 6, and the extension of the water passage 23 up to the top of the condenser 6 and connecting the same with the vent opening 28 leading to the atmosphere enables the condenser 6 to automatically vent itself whenever the pressure gets too high therein. Of course, should it be desired to do so, the vent opening 28 may be valved as usual. The goose neck 25 has its lower end 30 terminated near the bottom of the jacket 1, and thus when the liquid is being circulated in the jacket an efficient flow of the same through the jacket is had, which sweeps out any steam pockets which may have formed. The jacket is provided with a filling opening 31 having a closure 32 which is on a level with the liquid in the jacket, and therefore prevents the jacket from being filled to a point higher than the level 2. In this way, is the steam space 3 always preserved in the jacket. The tank 7 furnishes a reserve water supply sufficient to always maintain the level of the liquid in the jacket at the point 2, and thus it compensates for any leakage or loss of fluid.

It is obvious that those skilled in the art

may vary the operation of this device as well as the details of construction and the arrangement of parts without departing from the spirit of the invention, and therefore it is not desired to be limited to the above disclosure except as may be required by the claims.

What is claimed is:

1. The process of cooling a jacket of an internal combustion engine, which consists in filling said jacket with a cooling liquid to a predetermined normal level; heating said liquid beyond its point of vaporization, thereby raising said level; condensing the vapor thus produced and returning the condensed liquid to said jacket; circulating into and out of said jacket while said normal level of liquid is thus raised another portion of said liquid; and automatically ceasing the circulation of said second named portion of liquid when said normal level is not raised.

2. The process of cooling a jacket of an engine which consists in filling said jacket with a cooling liquid to a predetermined normal level; heating said liquid to its point of vaporization thereby raising said level; condensing the vapor thus produced and returning the condensed liquid to said jacket; circulating into and out of said jacket while said normal level is raised another portion of said liquid; maintaining substantially equal the pressures on the said two portions of liquid; and automatically ceasing the circulation of said second named portion of liquid when said normal level is not raised.

3. The process of cooling a jacket of an engine which consists in filling said jacket with a cooling liquid to a predetermined normal level; intermittently heating said liquid to its point of vaporization, thereby intermittently raising said liquid level; condensing the vapor thus produced and forcibly returning the condensed liquid to said jacket; forcibly circulating into and out of said jacket while said normal level is raised another portion of said liquid; automatically ceasing the circulation of said second named portion of liquid when said normal level is not raised; and conducting vapor to said condensed liquid when the circulation of said second named portion of liquid ceases.

4. In a cooling and condensing system, the combination of a jacket; means to fill said jacket to a predetermined normal level to provide a vapor space above said level; a condenser connected to said space; a pump; a connection between said condenser and said pump; a connection leading from said jacket at the normal level of said liquid to said pump; and a common return from said pump to said jacket.

5. In a cooling and condensing system for an engine, the combination of a jacket pro-

- vided with means for filling the same with a cooling liquid to a normal level and with a vapor space above said level; a condenser connected to said vapor space; a double impeller pump having a plurality of compartments; a connection between said condenser and one of said compartments; a connection leading from the normal level of said liquid in said jacket between said jacket and another of said compartments; and a common connection between said compartments and said jacket, substantially as described.
6. In a cooling and condensing system for an engine, the combination of a jacket provided with means for filling the same with a cooling liquid to a normal level and with a vapor space above said level; a condenser connected to said vapor space; a tank associated with said condenser; a double impeller pump having a plurality of compartments; a connection between said tank and one of said compartments; a liquid circulating connection between the normal level of said jacket and another of said compartments; and a common connection between said compartments and said jacket, substantially as described.
7. In a cooling and condensing system for an internal combustion engine the combination of a jacket provided with a cooling liquid; means for filling said jacket to a predetermined normal level; a condenser for reducing to the liquid form vapors arising from said liquid; a double impeller pump; means for drawing condensed liquid from said condenser into said pump and forcing the same back into said jacket; means leading from the normal level of liquid in said jacket for drawing liquid from said jacket into said pump, and forcing it back into said jacket through the same channel as said condensed liquid; and means for delivering both quantities of liquid near the bottom of said jacket, substantially as described.
8. In a cooling and condensing system for an internal combustion engine the combination of a jacket provided with a cooling liquid; means for filling said jacket to a predetermined normal level; a condenser for reducing to the liquid form vapors arising from said liquid; a double impeller pump; and connections between said condenser and said pump and leading from the normal level of liquid in said jacket to said pump by which one portion of liquid may be continuously returned to said jacket from said condenser while another portion of liquid may be circulated out of and into said jacket, substantially as described.
9. In a cooling and condensing system for internal combustion engines provided with a jacket, the combination of means to condense vapors evolved from said jacket comprising a tank; a diaphragm separating said tank from the condensing means; a vent for said tank; a pipe to return the condensed fluid to said jacket; a second pipe to lead cooling fluid out of said jacket; a third pipe to lead condensed fluid from said tank; an impelling means joined to said three pipes and adapted to maintain the pressures substantially equal in said second and third pipes, substantially as described.
10. In a cooling and condensing system for internal combustion engines provided with a jacket, the combination of means to fill said jacket to a predetermined normal level; means to condense vapors evolved from said jacket comprising a tank; a diaphragm separating said tank from the condensing means, and a vent for said tank; a pipe provided with a goose neck terminating near the bottom of said jacket to return the condensed fluid to said jacket; a second pipe to lead cooling fluid out of said jacket from the normal level thereof; a third pipe to lead condensed fluid from said tank; an impelling means joined to said three pipes, and adapted to maintain the pressures substantially equal in said second and third pipes, substantially as described.
11. In a cooling and condensing system for internal combustion engines, the combination of a jacket for containing a cooling liquid; means to fill said jacket to a predetermined normal level; a cooler connected to said jacket; means adapted to contain an excess supply of cooling liquid; a pump connected to said cooler and to said excess supply of liquid; and means connected to said pump and to said jacket at said normal level for limiting the level of said liquid in said jacket, substantially as described.

In testimony whereof I affix my signature.
WELLINGTON W. MUIR.
